CLAIM

I claim the ornamental design for a bread baking device, as shown and described.

DESCRIPTION

FIG. 1 is an elevated perspective view of the bread baking device of my claimed design;

FIG. 2 is a front view of the bread baking device of FIG. 1; FIG. 3 is a back view of the bread baking device of FIG. 1; FIG. 4 is a left side view of the bread baking device of FIG. 1;

FIG. 5 is a right side view of the bread baking device of FIG. 1;

FIG. 6 is a top view of the bread baking device of FIG. 1; FIG. 7 is a bottom view of the bread baking device of FIG. 1; and,

FIG. 8 is an elevated disassembled view of the bread baking device of FIG. 1.

The broken lines in FIG. 8 showing internal components of the bread baking device represent environmental structure and do not form any part of the claimed design.
